Primary Examiner — Garth Rademaker

(57) **CLAIM**

The ornamental design for a modular floral arrangement, as shown and described.

DESCRIPTION

FIG. 1 is a perspective view of a modular floral arrangement, showing my new design; and,

FIG. 2 is an exploded perspective view thereof.

The characteristic feature of the design resides in the modular nature of the vase element, which can be placed in multiple, different base elements. Such alternate base elements have not been shown and do not form a part of the claimed design.
